BREAKER BAR SCREEN MEANS FOR RIGID HAMMER ROTARY IMPACT CRUSHERS

John Chrystal, Columbus, Ohio, assignor to The Jeffrey Manufacturing Company, a corporation of Ohio

Application March 29, 1950, Serial No. 152,529

1 Claim. (Cl. 241—81)

1

This invention relates to a rigid hammer impact type crusher, and an object of the invention is to provide an improved crusher of this type with improved breaker bar screen means cooperating with the rotor.

A further object of the invention is to provide such a machine in which there is a bar screen located below the feed chute of said crusher operative to screen out small size material and to deliver large size material into the path of the rotor.

Other objects of the invention will appear hereinafter, the novel features and combinations being set forth in the appended claim.

In the accompanying drawings:

Fig. 1 is a side sectional elevational view of an impact crusher incorporating features of my invention;

Fig. 2 is a sectional view taken on the line 2—2 of Fig. 1, looking in the direction of the arrows;

Fig. 3 is a side view with parts in elevation and other parts in section, showing another form of impact crusher incorporating the features of my invention;

Fig. 4 is a plan view of the rotor, with parts broken away and in section;

Fig. 5 is a sectional view of an element of the rigid hammer holding means;

Fig. 6 is an end sectional elevational view of the machine of Fig. 3, showing chains across the feed chute;

Fig. 7 is an end view of the machine of Fig. 3, with parts broken away; showing particularly the pivotally adjustable breaker bar screen portion of the unit;

Fig. 8 is a sectional view taken along the line 8—8 of Fig. 3, looking in the direction of the arrows; and

Fig. 9 is a sectional view of the machine of Fig. 3, illustrating one possible condition of material undergoing a crushing action within the unit.

In the machine of Fig. 1 of the drawings, which incorporates some of the features of my invention, there is included a housing 10 formed of spaced side walls and front and back end walls, one of which merges into a top wall, all providing an enclosure having a feed chute 11. The feed chute 11 and the side walls of the housing 10 are provided with removable liner plates 12. Mounted for rotation within the housing 10 on a transversely extending horizontal axis is a rotor 13 having a shaft 14 carried at opposite ends on bearings, not shown, attached to the housing 10.

2

The rotor 13 includes a pair of similar diametrically opposite axially extending rigid hammers 15 which are mounted adjacent the periphery of the rotor 13 which is constructed to provide a reinforcing backing for said rigid hammers to withstand the heavy impact forces developed by the hammers 15 striking material, such as large stones and the like, when the rotor 13 is rotated in the direction of the arrows which is its operating direction of rotation.

The hammers 15 are preferably symmetrical so that when the radially outward edges become worn said radially outward edges may become the radially inward edges, and vice versa. The 15 radially inward edges of the rigid hammers 15 extend into radially-axially extending grooves 16 formed in the periphery of the body of the rotor 13 adjacent the bottom of the backing or reinforcing portions of said rotor which back up the rigid hammers 15.

As best illustrated in Figs. 1 and 2 of the drawings, the rigid hammers 15 have a pair of radially spaced keys 17 cast integral with them, the bases of which are flanged and extend into 25 axially extending grooves 18 (see Fig. 2) formed in the body of rotor 13. To clamp the rigid hammers 15 rigidly but removably to the body of rotor 13 there is a pair of aligned wedges 19 which extend into each of the grooves 18, said wedges 19 having oppositely tapering surfaces which cooperate with oppositely tapering surfaces of the grooves 18, as clearly illustrated in Fig. 2 of the drawings.

By drawing the wedges 19 axially toward each other by means of a wedging bolt 20 and its 35 clamping end nuts it is obvious that a wedging clamping action may be effected on the cooperating keys 17, thereby clamping the rigid hammers 15 tightly on the body of rotor 13. It may be mentioned in passing that this particular 40 clamping means, while quite satisfactory in many instances, does have a characteristic which is sometimes found objectionable which is overcome in the rigid hammer attaching means illustrated in the devices of Figs. 3 to 9, inclusive. For example, by referring to Fig. 2 of the drawings, it will be seen that as the wedges 19 are drawn toward each other they will exert equal and opposite forces on opposite sides of the groove 45 18 which will tend to expand this groove radially. This action, of course, means that the outermost portion of the body of the rotor 13, in other words, the portion immediately radially outward of each groove 18, is essentially a cantilever, and the base of this cantilever as attached

to the body of the rotor 13 is under stress, tending to break off the cantilever from the rest of the body of the rotor 13. This breaking off force developed by the wedges 19 is supplemented by the radially outward component of the centrifugal force developed by the relatively high speed rotation of the rotor 13 which conceivably could develop a dangerous situation in a very large machine, particularly if any crack or fault should develop at a critical area at the base of a groove 18. Under other circumstances, however, the particular form of attaching means for the rigid hammers 15, as illustrated in Figs. 1 and 2 of the drawings, is quite satisfactory.

Within the main body of the housing 10 and below the feed chute 11 and between one wall thereof and the rotor 13 there is a bar screen 21 including a plurality of spaced apart transversely or axially extending bars 22 which are relatively close together to provide a screening action for material delivered by the chute 11 to the interior of the housing 10 for reduction. The bar screen 21 slopes downwardly from a position below the feed chute 11 with the bottom thereof near to but spaced from the path of travel of the outer edge of each rigid hammer 15.

It is also to be noted that the bottom of the bar screen 21 is below a horizontal plane passing through the axis of the rotor 13, as a consequence of which large particles of material, such as stone, which are fed to the interior of the housing or casing 10, will be struck by a hammer 15 as it is traveling substantially vertically. The relatively fine material, or, in other words, any material which is of adequate fineness to pass through the screen 21, will do so and be discharged out the open bottom of the housing 10.

The reducing chamber 23 of the housing 10 is defined by the opposite side walls having liner plates 12 and by a breaker bar screen 24 which, as illustrated in Fig. 1 of the drawings, extends generally horizontally across the top of the housing 10 and curves downwardly, terminating at a position close to the rotor 13, being spaced a small distance from the outermost path of travel of the hammers 15.

The breaker bar screen 24 is made up of a plurality of breaker bars 25 which are preferably cylindrical in form, the axes of which extend transversely of the housing 10, or, in other words, parallel with the axis of the rotor 13. The bars 25 are close together, yet spaced apart so as to form a screen. It is to be particularly noted that the axes of the bars 25 are positioned to form points of a smooth concave curve which is generally horizontal adjacent the top of the housing 10 or the top of the reducing chamber 23, which curve then extends downwardly so that adjacent its bottom it is generally radial with the rotor as it approaches said rotor. In other words, a continuation of the curve formed by connecting the points which constitute the axes of the bars 25 from its lowermost position would pass through or substantially through the axis of the rotor 13 and shaft 14. This lowermost point of termination of the concave screen 24 is generally diametrically opposite the bottom of the screen 21 so that, roughly, half of the periphery of the rotor 13 is exposed to the material within the reducing chamber 23.

It is obvious that a substantial portion of the breaker bar screen 24 is spaced from the closest end or top wall of the housing 10 so that material which has been adequately reduced in

size by impact with the hammers 15 or the breaker bars 25 can pass through said screen 24 and fall by gravity out the open bottom of the housing 10. The bars 25 are carried in groups or individually on integral arcuate end plates 26 which are radially slidable into and out of holding and receiving grooves 27 formed in the liner plates 12.

Directly below the breaker bar screen 24 is an additional or supplementary breaker bar screen 28 which is made up of a plurality of transversely extending breaker bars similar to the breaker bars 25. This is essentially a supplemental breaker screen by which material which passes between the rotor 13 and the lowermost of the bars 25 may be subjected to a reducing action.

It is to be noted particularly that the screen 28 includes a lowermost breaker bar 29 which is adjustable by adjusting means 30 so that its clearance with reference to the rotor 13 may be adjusted. It is furthermore to be noted that its clearance with the rotor 13 is considerably less than that between the lowermost breaker bar 25 and said rotor 13. Consequently any large particles which may get past the lowermost breaker bar 25 cannot be discharged until reduced adequately to clear the screen 28 or pass between the bar 29 and the rotor 13.

In Figs. 3 to 9, inclusive, of the drawings, another form of impact crusher incorporating the features of my invention is disclosed. This machine incorporates a number of the features above described and also includes important features of my invention which are not embodied in the machine of Figs. 1 and 2.

The machine of said Figs. 3 to 9, inclusive, includes a housing or casing 31 having a pair of parallel laterally spaced upright side walls 32,32 provided with removable liners 33. The housing or casing 31 also includes a transversely extending upright end wall 34, the upper portion of which is provided with removable liners 35. Opposite the end wall 34 is an end wall 36 which curves into an integral top wall 37. The side, end and top walls are all rigidly attached together and are supported on and removably attached to a heavy rectangular base 38 which may be anchored above an opening in the supporting floor, through which opening reduced material is discharged from the open bottom of the housing or casing 31.

Within the housing 31 there is a rotor 39 which, as illustrated, is built up of a plurality of steel discs 45 stacked on a rotor shaft 40 and keyed thereto. The rotor 39 is supported for rotation on a transverse horizontal axis by spaced bearings carried in appropriate bearing boxes 41 at opposite sides of the housing 31. A selected one of the side walls 32 is provided with a feed chute 42 which, if desired, may be provided with chain screen 43. Opposite the chute 42 is a removable door interchangeable therewith. The top wall 37 is preferably provided with removable liner or breaker plates 44 directly above the feed chute 42.

Within the housing 31 and spaced from the adjoining end and top walls 36 and 37 there is a breaker bar screen 45 which has the same essential characteristics as the breaker bar screen 24 above described in connection with the device of Figs. 1 and 2. That is, it is made up of a plurality of closely adjacent but spaced apart breaker bars 46 preferably of cylindrical shape, which extend transversely or axially of the rotor

between the side walls 32. The axes of said bars 46 are points along a smooth concave curve which is generally or substantially horizontal at the top of the chamber 31 where it is radially the greatest distance from the axis of the rotor 39, this curve being substantially radial with the rotor 39 at its bottom.

The bars 46 are provided with individual end plates by which they are slidably carried in guides on the opposite side walls 32 provided by liners 33 and guide ribs 41. The breaker bars 46 may be inserted and removed by extending them transversely through an opening 48 (see Fig. 3) in one of the side walls 32, which opening may be closed by a filler type cover plate after the breaker bars 46 are all inserted. They may be clamped with their end pieces held tightly together by abutting clamping bars 49 and associated clamping screws 50.

There is one difference between the breaker bar screen 24 of the device of Figs. 1 and 2 and the breaker bar screen 45 of the device of Figs. 3 to 9; that is, as clearly illustrated in Fig. 9, there is a larger and heavier breaker bar or anvil 51 which is the lowermost of those forming the screen 45 or which is the closest of this screen to the rotor 39 it being closely adjacent the hammer circle of said rotor 39. The breaker bar 51 is not inserted, as are the breaker bars 46, but it is carried at opposite ends in receiving cups on the side walls 32 and is individually removable laterally through holes in the side walls 32 covered by the cover plates 52. It has been found desirable to make this breaker bar 51 heavier than the others because it is subjected to severe shocks occasioned by large particles being caught between it and one of the rotor hammers.

Below the feed chute 42 there is a bar screen 53 which, as illustrated, is formed by a plurality of parallel laterally spaced downwardly sloping screen bars 54 which extend at right angles to the axis of the rotor 39 and are held together by a pair of transversely extending rods 55. If desired, the form of bar screen illustrated at 21 may be employed in this position. It is to be noted that the bar screen 53 extends from the end wall 34 sloping downwardly therefrom to a position close to the rotor 39, the bottom thereof being below a horizontal plane passing through the axis of said rotor 39. This cooperates with the breaker bar screen 45 to provide a large reducing chamber 56 in which substantially 180° of the rotor 39 is exposed to the material undergoing reduction.

Below the bar screen 45 there is another or supplemental bar screen 57, which as illustrated, includes three cylindrical transversely extending breaker bars 58 extending between and rigidly attached to end plates 59. The top-most of the breaker bars 58 extends axially beyond the end plates 59 and through sleeves 60 (see Fig. 7) formed integral with the plates 59, which sleeves 60 are journaled in appropriate journal bearings formed on the base 38. This top breaker bar 58 is keyed or otherwise rigidly attached to the sleeves 60 and at one end is provided with a locking collar 61, the other end being provided with an upstanding lever 62 bolted thereto. Lever 62 is keyed by a shear pin 63 at any one of a plurality of positions provided by threaded openings in a pair of spaced apart holding straps 64 between which lever 62 extends and which are attached to and spaced from one of the side walls 32 of the housing 31.

By adjusting the lever 62 the clearance be-

tween the bottommost breaker bar 58 and the rotor 39 may be adjusted. This bottommost breaker bar 58 is preferably heavier than the other two since it is subjected to more severe shocks. The shear pin 63 constitutes an overload release in case too severe a shock is transferred to the lowermost breaker bar 58. The adjustability of the screen 57 provided by the lever 62 makes for a rough adjustment of the fineness of the material produced. A stationary transversely extending plate 71 extends between the bottom of the screen 45 and the screen 47 and in effect forms a stationary part of said supplementary screen 57.

Attention is now directed particularly to Figs. 3, 4, 5 and 6 and to certain significant details of construction of the rotor 39. As above set forth, the body of the rotor 39 may be built up of a plurality of heavy steel discs 65 stacked on the shaft 40 and keyed thereto. The discs 65 are also preferably tack welded together. At diametrically opposite positions the body of the rotor 39 is provided with peripheral axially extending grooves 66 adapted to receive rigid hammers 67 which, as illustrated, are two-piece members (see Fig. 6).

The rotor body is so formed that the leading edge and a substantial portion of the leading face of each of the hammers 67 is exposed so that it may strike the material, such as stone, to be reduced. The rear or trailing side or face of each hammer 67 is provided with an axially extending groove 68 adapted to receive a projecting tongue 69 formed on the back or trailing face of the groove 66 and on a backing or reinforcing portion of the body of the rotor 39. The tongue 69 and groove 68 cooperate so that it is impossible for the rigid hammer 67 to be inserted or removed radially from the groove 66, having regard for the depth of groove 66, the limited clearance provided by the opposite walls of said groove 66, and the pertinent dimension (thickness) of the hammer 67. This interlock prevents the hammer 67 flying off the rotor 39 in case its holding means, hereinafter described, becomes broken or inoperative for any reason.

As above stated, each of the rigid hammers 67 is made up in two parts. In other words, it is split at its longitudinal center, the two parts being individually removable by being moved axially of the rotor 39 in opposite directions. To hold each rigid hammer 67 removably to the body of the rotor 39 a one-piece symmetrical tie rod 70 is provided, the center of which is bolted adjacent the axial center of the body of the rotor 39 within the groove 66. Each half of the rigid hammer 67 is of similar construction and is hollow and is adapted to slide over the laterally extending wings of the tie rod 70, said hammer halves and tie rods having cooperating frusto-conical bearing areas so that when clamped in position the rigid hammer halves are held rigidly to said tie rod 70.

At each outer end of each tie rod 70 there is a pivoted clamping strap 71 having integral frusto-conical projections 72 and 73 adjacent opposite ends thereof. The projections 72 are received in cooperating frusto-conical bearing areas of the hollow rigid hammers 67 to which the straps are rigidly but removably clamped by nuts cooperating with the threaded ends of the wings of the tie rods 70. The frusto-conical projections 73 are received in similar recesses in the body of the rotor 39. Machine screws 74 ex-

tend freely through the clamping straps 71 and are threaded into the body of the rotor 39.

The parts are so dimensioned that as the screws 14 are tightened a clamping action will be effected so as to place the straps 71 under tension, thereby pulling the rigid hammers 67 against one of the side walls of the groove 66 and away from the opposite side wall thereof. In other words, this tension on the side straps 71 effects a tight engagement between the areas defining the tongue 69 and the groove 68.

The ends of the body of the rotor 39 are provided with appropriate receiving pockets 75 so that the ends of the tie rods 70 do not extend axially beyond the ends of the body of the rotor 39 and so that the straps 71 and machine screws 14 are within the axial dimensions of the body of said rotor 39, thus protecting all of these parts from damage. The rigid hammers 67 are also formed at their outer ends so as to shroud or protect the clamping parts just mentioned as clearly illustrated in Fig. 4 of the drawings.

It is particularly significant to note that in this construction there are no forces tending to spread the groove 66. Likewise the portion of the rotor body 39 which backs up or reinforces the rigid hammers 67 and which constitutes a cantilever is not subjected to any strain because of any clamping means for the rigid hammers. This is believed to be of considerable importance and constitutes a feature of my invention.

The two parts of the rigid hammers 67 may be removed through the opposite side walls 32 which are provided with access openings and removable cover plates 76 (see Fig. 6) which are essentially similar to the cover plates 52 and that provided for the opening 48. No claim is made to any of these features for removing parts of the crusher which may become worn, as this has been standard practice for many years in connection with similar construction providing for the ready axial removability of breaker bars, hammer pins, and equivalent parts of crushers which become worn in operation.

In the operation of the crusher of Figs. 1 and 2 or of Figs. 3 to 9, material to be reduced which may be any hard friable material, of which stone is illustrative, will be delivered to the interior of the housing 10 or 13, as the case may be, through the feed chute 11 or 42. Most of the fine material will escape radially through the screen 21 or 53, as the case may be, and be discharged through the open bottom of the housing. The oversize material incapable of passing through this screen will be struck a shattering blow by one of the rigid hammers of the rotor, which rotor will be traveling at a relatively high speed in the direction indicated by the arrows. The rigid hammers on striking the material will initially shatter it and propel it through the reducing chamber where it will strike a liner or breaker plate of the reducing chamber, such as the liner 12, 33, 35 or 44, or some of it may strike the breaker bar screen 24 or 45, as the case may be, following the initial impact of the rigid hammer.

Material which strikes the breaker bar screen 24 or 45 and which is adequately reduced to pass through said screen may do so whereupon it will

be free to fall downwardly through the housing and out the bottom thereof. Oversize material will be retained in the reducing chamber until adequately reduced to pass through this screen or the screen 21 or 53, as the case may be, or some of it may pass below the breaker bar screen 24 and be further treated until it can pass through the screen 28 or 51, as the case may be.

The structure of the rotor, hammers and holding means therefor is claimed in my divisional application, Serial No. 230,862, filed May 15, 1951.

Obviously those skilled in the art may make various changes in the details and arrangement of parts without departing from the spirit and scope of the invention as defined by the claim hereto appended, and applicant therefore wishes not to be restricted to the precise construction herein disclosed.

Having thus described and shown an embodiment of the invention, what it is desired to secure by Letters Patent of the United States is:

A rigid hammer crusher including a housing having a feed opening, a rotor in said housing, a rigid hammer attached to the said rotor and extending radially beyond the periphery of the rotor and axially thereof, a breaker bar screen including a plurality of spaced apart closely adjacent breaker bars in said housing spaced radially from said rotor, said breaker bars extending parallel with the axis of said rotor and positioned so that their axes form points of a smooth concave curve which extends downwardly from a top generally horizontal position above said rotor to a bottom position closely adjacent said rotor, said curve being generally radial with said rotor as it approaches it, said curve also being concave relative to the line of trajectory of material struck and impelled by said rigid hammer, and a bar screen located below said feed opening and sloping downwardly from a wall of said housing to a position adjacent said rotor, the lower edge of said bar screen being below a horizontal plane through the axis of said rotor.

JOHN CHRYSSTAL.
